UNITED STATES PATENT OFFICE.

HENRI CROIZIER, OF PARIS, FRANCE.

APPARATUS FOR DRYING POWDERS.

SPECIFICATION forming part of Letters Patent No. 761,763, dated June 7, 1904.

Application filed October 4, 1901. Serial No. 77,618. (No model.)

To all whom it may concern:

Be it known that I, HENRI CROIZIER, a citizen of the French Republic, residing at 9 Rue de Mogador, Paris, in the French Republic, have invented a new and Improved Apparatus for Drying Powders, of which the following is a specification.

For certain applications it is well known that it is necessary to heat sand or other powdery substances. Various apparatuses have been proposed hitherto; but they are generally expensive and cumbersome.

The present invention relates to a new arrangement for drying sand or other powdery substances and is characterized, essentially, by utilizing the waste heat of the smoke escaping from any kind of fire into the chimney. The sand is raised to the top of the chimney by any suitable means and allowed to fall in a fine shower through the smoke rising in the chimney. The dry sand is collected at the lower part of the chimney in any suitable kind of receiving-chamber. It is to be understood that the means for bringing the sand to the top of the chimney and the arrangement of the receptacle for the dry sand, &c., may be modified according to the arrangements of the factories where the process is employed.

30 A practical form of an arrangement for carrying this invention into effect is illustrated, by way of example, in the accompanying drawings.

Figure 1 is an elevation of the chimney. Fig. 2 is a part sectional elevation of the chimney on an enlarged scale. Fig. 3, which illustrates a corner of the chimney on an enlarged scale, is for the purpose of showing certain details, notably the arrangement of the heat-insulating material and the disposition of the bafflers.

As will be seen, the chimney consists of superposed cast sections *a*. The whole is supported by three or more stays *b* with coupling-screws *c*, said stays being anchored as firmly as possible in the ground at *d*. The sand is raised in the conduit *e* by any suitable means—for instance, by a chain-pump—and falls in a fine shower through the spout *f* at the top of the chimney. The shower is broken

up by the bafflers *g*. These bafflers *g* in order to oppose as little resistance as possible to the escape of the smoke are constructed of tubes; but it is to be understood that any other suitable arrangement could be employed. 55 Thus in Fig. 3 (referring also to Fig. 2) bafflers of different kinds are shown by way of example, one consisting of an oblique channel and the other of a tube.

h is the aperture through which the smoke 60 enters from the furnace.

The dry sand falls at *i* into the receptacle, whence it can afterward be removed through the hopper *j*, and it can be sifted eventually by means of suitable sieves. 65

Windows *k*, provided with mica, glass, or other transparent material, are arranged in the lower compartment, which allows the quantity of sand it contains to be ascertained.

The upper part of the chimney is provided 70 with a sheet-iron chimney *l*, which increases the draft in order to compensate for the losses produced by the meeting of the smoke with the falling sand and with the bafflers for distributing the sand. The sheet-iron chimney 75 *l* is provided with ties *m*.

In order to prevent cooling, the outer part of the chimney is provided with a heat-insulating coating *o*, supported by sheet-iron or other material *p*. This casing is attached to 80 the stays *b*, as shown in Fig. 3.

It is understood that any suitable means may be employed for connecting together the various sections forming the chimney.

It is obvious that in certain cases it will not 85 be necessary to raise the sand to the top of the chimney by means of a conveyer. This will be the case, for instance, when the store of sand is higher than the top of the chimney, as when the factory is situated close to elevated 90 ground. In this case the sand can pass down a natural declivity to the level of its entrance to the chimney.

What I claim is—

1. In means for drying powdery materials 95 the combination of a chimney carrying away the gases of any industrial fireplaces and consisting of superposed cast sections provided with a heat-insulating coating, a spout introducing the said powder, tube-bafflers arranged 100

in zigzag for producing a shower of the powder down said chimney and stays anchored in the ground fastening the sections together, substantially as described.

- 5 2. In means for drying powdery materials the combination of a chimney carrying away the gases from any industrial fireplaces and consisting of superposed cast sections provided with a heat-insulating coating, a spout introducing the said powder, tube-baffles arranged in zigzag for producing a shower of the powder down said chimney and stays anchored in the ground fastening the sections together

the first section from the bottom containing the hopper for carrying away the dried materials, the second being provided with peep-holes and the third containing the entrance for the hot gases, substantially as described. 15

In testimony whereof I have signed my name to this specification in the presence of two subscribing witnesses. 20

HENRI CROIZIER.
